SPRAY GUN UNIT

George D. Shelton, Riverside, Calif.

Application February 13, 1959, Serial No. 54,596

Term of patent 14 years

(Cl. D62—2)

FIG. 1.

FIG. 2.

FIG. 3.

FIG. 4.

FIG. 5.

FIG. 6.

Figure 1 is a left side elevation of a spray gun unit embodying my new design;

Figure 2 is a top plan view thereof;

Figure 3 is a front elevation;

Figure 4 is a right side elevation;

Figure 5 is a bottom plan view thereof; and

Figure 6 is a rear elevation.

I claim:

The ornamental design for a spray gun unit, as shown.
